UNITED STATES PATENT OFFICE.

JAMES C. FARRINGTON, OF LA FAYETTE, INDIANA.

KNOCKDOWN TRELLIS.

Application filed June 16, 1926. Serial No. 116,301.

The object of my invention is to produce from metallic parts which may be compactly packed for shipment and readily assembled and erected by an average householder, an ornamental trellis.

The accompanying drawings illustrate my invention. Fig. 1 is a perspective of my improved trellis partially assembled; Fig. 2 a fragmentary view showing the manner of association of the vertical wires and supporting cross bars; Fig. 3 a fragmentary view showing the manner of association of the vertical wires and the lower cross bar, Fig. 4 a perspective showing the parts packed for shipment; Fig. 5 a perspective view of a modified form of lower cross bar, and Fig. 6 a perspective view of the Z-bracket.

In the drawings 10 indicates a suitable length of ordinary commercial angle iron of suitable dimensions and preferably sharpened at its lower end, as indicated at 11 in order to facilitate entry into the ground.

A plurality of cross arms 12 is provided, each consisting of a strip of metal having a portion 13 at its middle twisted into a plane at right angles to the ends and perforated to receive a fastening bolt 14 projectible through a suitable perforation in one leg of the angle 10. The ends of the bars 12 are perforated with a suitable number of spaced perforations 15 through which may be projected the vertical wires 16. Said wires are most conveniently formed by doubling a suitable length into hairpin shape so as to form an eye 17 through which a fastening bolt 18 may be passed, said bolt also passing through a suitable perforation in the lower cross bar 19 secured by one of said bolts 18 to an arm of post 10.

The arms of the "hairpins" 16—17 may be straight or kinked but, both for the ornamental effect and for the sake of strength I have found it desirable to form therein short kinks by heavy impact, such manipulation serving to very substantially stiffen the wires and thus make possible the use of a smaller sized wire than would otherwise be practicable.

Bars 12 and 19 and the wires 16—17 may be readily packed in the angle of the post 10 and held therein by binding wires 20 as indicated in Fig. 4 so that the parts may be shipped in a minimum space. Any average householder may without difficulty assemble

the parts as shown in Fig. 1 with the aid of a screw driver and wrench.

The shape of the completed structure may be very substantially varied by varying the 60 lengths of the various cross bars and the distances between, and the arrangement of, the perforations 15.

When the parts have been assembled as shown in Fig. 1 the lower end of the post 10 65 may be readily driven into the ground by striking the upper end of the post.

In Fig. 5 I show a cross bar 19' which may be used instead of the cross bar 19, especially in the lighter constructions. This 70 cross bar 19 is sheet metal with struck-up tongues 25 beneath which the wires 16 may be hooked and the tongues then bent down to retain the wires in place. In order to place the trellis in position relative to a 75 house or porch, the upper end of bracket 10 is perforated at 30 so that it may be secured to the downwardly projecting arm 31 of a Z-bracket 32, the upper arm being readily attachable to the building. In case of 80 needed height a length of angle iron similar to post 10 may be driven into the ground and post 10 secured thereto by means of bolts passed through perforations 34.

There is, of course, a decided objection to 85 the utilization of an ordinary metallic support for growing plants because of the heat absorption and retention of the metal.

In my present construction this difficulty has been overcome. First, because the cross 90 bars, being perforated, there is sufficient circulation of air therethrough to keep the temperature low and, second, by forming the wire 16 from a copper-bearing alloy, 95 radiation is sufficiently rapid to keep the temperature low.

I claim as my invention:

1. A knock-down trellis comprising a post, a plurality of cross bars detachably secured thereto at various points in its 100 length, intermediate of its ends, said cross bars being provided with a plurality of spaced perforations, and a plurality of relatively high heat-radiant wires threaded through and retained in said perforations 105 in such manner as to permit free air circulation through said perforations.

2. A knock-down trellis comprising a metallic angle post, a plurality of cross bars detachably secured thereto at various points 110 in its length, said cross bars being provided with a plurality of spaced perforations, and

a plurality of wires threaded through and retained in said perforations.

3. A knock-down trellis comprising a metallic angle post, a plurality of cross bars each having a middle portion twisted into a plane at an angle to the plane of the ends and the ends being perforated by a plurality of spaced perforations, means by which said cross bars may be detachably attached 10 to the post, another cross bar and means for detachably attaching said second-mentioned cross bar to the post, a plurality of wires doubled upon themselves and of a size capable of projection through the perforations of the first-mentioned cross bars, and means by which the said wires, at their point of doubling, may be detachably secured to the second-mentioned cross bar.
4. A trellis comprising a post, a plurality 20 of cross bars secured to said post at various points in its length intermediate of its ends and provided in their ends with a plurality

of spaced perforations, and a plurality of kinked wires projected through said perforations and retained therein to form a plurality of substantially vertical trellis members, the perforations being of such character as to permit free air circulation. 25

5. A trellis comprising a post, a plurality of cross bars secured to said post at various 30 points in its length and provided in their ends with a plurality of spaced perforations, another cross bar secured to the post, a plurality of kinked wires doubled upon themselves and their ends projected through the 35 perforations of the first-mentioned cross bars, and means associated with the second-mentioned cross bar for retaining said wires in place.

In witness whereof, I have hereunto set 40 my hand at La Fayette, Indiana, May, A. D. one thousand nine hundred and twenty-six.

JAMES C. FARRINGTON.
